CLAIM

I claim the ornamental design for a hairdryer, as shown and described.

DESCRIPTION

FIG. 1 is a front-right perspective view of a first embodiment of a hairdryer, showing my new design;

FIG. 2 is a rear-left perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The dash-dot broken lines in the drawings depict the bounds of the claim which extends to the dash-dot broken lines but does not include the dash-dot broken lines, while all other broken lines depict portions of the hairdryer that form no part of the claimed design. All broken lines form no part of the claim.
